[57] CLAIM

The ornamental design for a jewelry storage rack, as shown and described.

DESCRIPTION

FIG. 1 is a front elevational view of a jewelry storage rack showing my new design;

FIG. 2 is a right side elevational view thereof, the left side being a mirror image of that shown;

FIG. 3 is a top plan view thereof, the bottom being a mirror image of that shown;

FIG. 4 is a rear elevational view thereof; and

FIG. 5 is a vertical cross-sectional view thereof, taken along line 5—5 of FIG. 1.

FIG. 4

FIG. 5
